UNITED STATES PATENT OFFICE.

WILLIAM A. MUNDY, OF PHILADELPHIA, PENNSYLVANIA.

SKYLIGHT.

1,053,633.

Specification of Letters Patent.

Patented Feb. 18, 1913.

Application filed July 28, 1909. Serial No. 510,066.

To all whom it may concern:

Be it known that I, WILLIAM A. MUNDY, of Philadelphia, in the State of Pennsylvania, have invented a certain new and useful Improvement in Skylights, wherof the following is a specification, reference being had to the accompanying drawing.

It is the object of my invention to provide a translucent cover for roof openings, which are ordinarily covered by frames containing separate panes of glass. Such ordinary devices are disadvantageous in that it is practically impossible to prevent seeping of water around the edges of the glass panels at the joints in the frame or sash.

As hereinafter described, my invention provides a cover of the class contemplated, formed of a single casting of glass having flanges at its edges respectively fitted for attaching means and to direct the water from the upper surface of the cover beyond said attaching means.

My invention includes the various novel features of construction and arrangement hereinafter more definitely specified.

In the drawing, Figure I is a plan view of a skylight conveniently embodying my improvement. Fig. II is a transverse sectional view of said skylight. Fig. III is a sectional view, similar to Fig. II, but showing a modified form of the invention.

In said figures: the roof 1 is covered with any suitable waterproof material 2, and has the skylight opening 3, surrounded by the vertical flange 4.

As shown in Figs. I and II my improved cover includes a plane panel or web of glass 5 having the unitary marginal flange 6 depending transversely with respect to the margins of said web, so as to direct rain or other moisture from the upper surface of said web clear of the unitary inner attaching flange 7, which as shown in Fig. II is fitted over the roof flange 4 which has at its upper edge the gasket 8 upon which said web rests. The bolts 9 which extend through said flanges 4 and 7 are provided with nuts 10 so as to detachably secure said cover in the closed position shown in Fig. II.

The form of my invention, above described, provides a cover which is prac-

tically hermetically sealed in connection with the roof and may be conveniently employed upon inclined roofs. However, I find it convenient to employ upon flat roofs 55 a cover which is arched, as indicated in Fig. III, so as to shed water therefrom. Moreover, the cover shown in Fig. III may be advantageously employed where it is desired to ventilate a building through the 60 skylight, said cover having a series of apertures 14 in the flange 15 extending above the vertical flange 16 of the roof, but being otherwise constructed and attached like the form of my invention shown in Figs. I and 65 II.

I do not desire to limit myself to the precise details of construction and arrangement above described, as it is obvious that various modifications may be made therein 70 without departing from the essential features of my invention, as defined in the appended claims.

I claim:—

1. In a skylight, a panel of molded glass 75 having a marginal flange depending transversely with respect to the edges of the panel; a second flange depending approximately parallel with the marginal flange aforesaid within the latter, and having openings 80 for attaching means; and air vent openings in said inner flange between said openings for attaching means and said panel.

2. In a skylight, a unitary cover formed of translucent molded material including a 85 web having a marginal flange extending transversely with respect thereto, and a second flange extending substantially parallel with said marginal flange within the latter and having respective openings for attaching 90 means and constituting air vents.

3. The combination with a roof having an opening with a marginal flange; of a skylight including a web having a depending attaching flange arranged to register with 95 said roof flange; an exterior marginal flange on said web arranged to direct moisture away from said attaching flange and means extending through said attaching flange on said panel and the flange on said 100 roof, including removable screw threaded members; said attaching flange on said

panel having air vents opening through it between said web and the upper edge of said roof flange.

4. In a skylight, a panel of translucent material having a marginal flange depending transversely with respect to the edges of the panel; and, attaching means affording air vents beneath said flange.

In testimony whereof, I have hereunto signed my name at Philadelphia, Pennsylvania this tenth day of July, 1909.

WILLIAM A. MUNDY.
